CLAIM

The ornamental design for a maraca or rattle, as shown and described.

DESCRIPTION

FIG. 1 is a front view of a maraca or a rattle embodying my new design; and,

FIG. 2 is a side view thereof, the undisclosed opposite side being a mirror image.

The rear of the maraca or rattle, not shown in the drawing or described in the specification, forms no part of the claimed design,

Use of the design as an adult maraca or a child's rattle is determined by the size of the article.
